ELECTRODE

Gustav Adolph, Solln, Germany, and Max E. Bretschger, Buffalo, N. Y., assignors to Buffalo Electro-Chemical Company, Inc., Buffalo, N. Y.

Application November 12, 1936, Serial No. 110,520

4 Claims. (Cl. 204—289)

This invention relates to an electrode and particularly to an anode suitable for the production of percompounds by anodic oxidation.

In the production of percompounds, such as persulfuric acid, perboric acid, etc., and their salts, it has been found that platinum anodes must always be employed as all other metals do not permit of a deposit of the desired anion on the acid or its salt, such as SO_4 on sulfuric acid or a salt thereof, even though the metal might be sufficiently stable against attack by the electrolytic solution.

Because of the high price of platinum, it has always been the endeavor of the trade to construct anodes employing the minimum amount of platinum, or to replace platinum wherever possible with cheaper materials. Thus, the current conducting rod has been made of copper or other highly conducting materials. However, where common metals, copper for instance, are used as the conducting rod, the common metal must be protected against attack of the anode solution and the nascent oxygen adjacent thereto by more or less efficient coatings or coverings impervious to attack by these chemicals. Hard rubber has been found to be an efficient coating material.

In all these cases, however, the coating material is subject to attack in the course of time by the nascent oxygen developed at the platinum conductance wire, forming a channel therein pervious to the solution whereby the copper lead rod would be prone to attack with the ultimate destruction of the contact between the copper lead wire and the platinum tip.

It is an object of the present invention to eliminate the possibility of attack of the hard rubber coating by nascent oxygen and protect the contact between the conducting core rod of common metal and the anode tip of platinum.

Other and further objects and advantages of the invention will appear hereafter and be more particularly pointed out in the claims.

The drawing shows a view in perspective of the improved anode.

Referring more particularly to the drawing, the anode of the present invention is formed of a central conducting core or rod 10 of a common metal, as, for instance, copper. Electrical contact and connection is made between rod 10 and a conducting element 11 of metallic tantalum. Surrounding and enclosing copper core or rod 10 is a hard rubber sheath 12 formed with lips 13 which engage the tantalum member 11. The anode is completed by connecting the platinum tip 14 to the tantalum member 11.

It will be seen from the foregoing that the present invention provides an anode wherein a

minimum of platinum is used and an anode wherein attack of the hard rubber sheath or covering over the copper conductor has been eliminated by the interposition of the tantalum member 11 between the copper core 10 and platinum tip 14 since tantalum is a good electrical conductor but, however, no nascent oxygen is developed upon the tantalum and, further, the tantalum member is stable against and toward the electrolyte, which property is described in German Patent No. 386,514.

What is claimed is:

1. An anode for the production of percompounds comprising a core of conducting material, a sheath of non-conducting material stable toward the electrolyte of the bath in which the anode is used surrounding the core, a platinum tip upon which nascent oxygen develops when the anode is used in the production of percompounds spaced from the sheath, and a member of tantalum extending through the sheath and being connected electrically to the core and to the platinum tip so that when in use no nascent oxygen develops in contact with the sheath.

2. An anode for the production of percompounds comprising a core of copper, a sheath of non-conducting material surrounding the copper core, a platinum tip spaced from the sheath and a member of tantalum extending through the sheath and having electrical contact with the core and the platinum tip so that when the anode is used for the production of percompounds nascent oxygen develops only upon the platinum tip and not in contact with the sheath.

3. In an electrode, an elongate element of conducting material, a second elongate element of electrochemically active conducting material extending parallel thereto and spaced therefrom, an insulating sheath surrounding said first element, and a plurality of electrochemically inactive conductors extending through said insulating sheath and between said two elements for maintaining rigid relation and for establishing electrical communication therebetween.

4. In an electrode, an elongate element of a metallic conducting material, a second elongate element comprising electrochemically active conducting material of platinum extending parallel to said first element and spaced therefrom, an insulating sheath surrounding said first element, and a plurality of electrochemically inactive conductors formed of tantalum and extending between said two elements for maintaining rigid relation and for establishing electrical communication therebetween.

GUSTAV ADOLPH.
MAX E. BRETSCHGER.
